UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

VARIABLE-ESCAPEMENT MECHANISM.

1,178,112.

Specification of Letters Patent.

Patented Apr. 4, 1916.

Original application filed July 11, 1912, Serial No. 708,859. Divided and this application filed March 12, 1913. Serial No. 753,804.

To all whom it may concern:

Be it known that I, OTTO THIEME, a citizen of the United States, residing at the city of St. Louis, State of Missouri, have invented a certain new and useful Improvement in Variable-Escapement Mechanism, of which the following is a full, clear, and exact description, such as will enable others skilled in the art to which it appertains to make and use the same, reference being had to the accompanying drawings, forming part of this specification, in which—

Figure 1 is a front elevational view of my improved mechanism showing it applied to one form of calculating machine. Fig. 2 is a side elevational view of the mechanism illustrated in Fig. 1, certain parts having been removed. Fig. 3 is a detail view of the pallets which coöperate with the escapement teeth. Fig. 4 is a detail view of the fixed pallet. Fig. 5 is a detail view of the key operated stops which regulate the throw of the escapement mechanism.

My improvement relates particularly to key operated machines, and specifically to a form of escapement mechanism particularly adapted to use on combined calculating and writing machines, commonly known as "billing machines".

The principal object of my invention is to provide a simple and efficient escapement mechanism for the laterally movable carriages of key operated machines, and one which is not susceptible to overthrow or dis- placement.

Another object of my invention is to provide means whereby the laterally movable carriage may be stepped leftwardly two or more spaces simply by the operation of a single key, and without the use of stops positioned independently anticipatory to the operation of such key.

Another object of my invention is to provide in such a mechanism a plurality of keys each of which is adapted to letter-space the carriage to a different extent.

Other and further objects of my invention will be pointed out in the description, reference being made to the accompanying drawings, or will be obvious from inspection thereof.

This application is a division of my co-

pending application filed in the United States Patent Office July 11, 1912, Serial Number 708,859.

55

In the accompanying drawings, I have shown my invention applied to the form of calculating machine such as is disclosed in Belgian Patent No. 20,281, dated August 21, 1907, and adapted to regulate the lateral movement of the laterally movable pin carriage which constitutes a portion of the calculating mechanism described in the aforesaid patent. It is obvious, however, that this is but one of the many possible applications of my invention, and that it may with equal facility be adapted to regulate the letter-spacing movement of the paper carriage of a writing machine, or any similar laterally movable portion of such machines which is desired to be moved in a step by step movement.

In the form illustrated, 1 indicates a portion of the machine frame upon which are carried track bars 58 upon which the carriage 4 is mounted to travel on the roller bearings 57^a. As described in said patent, there is a spring, not shown in the accompanying drawings, for drawing the carriage 57 leftwardly when it is released by operation of the escapement mechanism. Bars

56 coöperate with the carriage 57, and are operable by key levers 2, and these parts are adapted to effect upon elements carried by the carriage 57 operations which require each a single leftward step of the carriage. Bar 56' is operable by key lever 15' and is adapted to effect upon elements carried by the carriage 57 operations requiring a letter-spacing movement of the carriage of a single step.

Bar 56'' is operable by key lever 15'' and is adapted to effect upon elements carried by the carriage 57 an operation requiring letter-spacing movement of said carriage equal to two steps. Bar 56''' is operable by key lever 15''' and is adapted to effect upon elements carried by the carriage 57 an operation requiring a letter-spacing movement of the carriage corresponding to three steps. Bar 56'''' is operable by key lever 15'''' and is adapted to effect upon elements carried by the carriage 57 operations requiring a letter-spacing movement of the carriage to an extent corresponding to four

65

85

90

steps. Key bars 15", 15''' and 15'''' are operable by multiple space keys 02, 03 and 04. The carriage 57 carries a rack 78 which has the teeth 4 corresponding to the letter-space steps of the carriage.

5 Mounted to coöperate with the teeth 4 of the rack 78 are bar 6 carrying a fixed escapement pallet 5, and link 8 carrying movable escapement pallet 7. Bar 6 is capable 10 of up and down reciprocating movement only, while link 8 may be moved longitudinally and oscillated vertically by virtue of its slotted pivotal mounting on track bar 58. Bar 6 is drawn downwardly by a spring 12, 15 and is provided at its lower extremity with a foot portion 6' which extends cross key levers 2, 15', 15", 15''' and 15'''', and acts as a universal bar which is engaged by any 20 of the key levers when a key is pressed down. By such an operation of any of the key levers, bar 6 is raised so as to bring fixed pallet 5, which normally lies out of engagement with the rack 78, into engagement with said rack, whereby to hold carriage 57 against lateral displacement under influence of the carriage spring.

30 The means for controlling the variable or differential spacing of the carriage leftwardly consists of a lever 16 pivoted on a suitable bracket secured to the base of the machine and having one end lying over the rear ends of bars 15", 15''' and 15''''. This lever is notched at the upper edge of that portion which extends over the bars mentioned, for the purpose of differentially engaging stop plates 17 and 18 which are pivotally mounted at their lower ends to bracket extensions secured to the base 1, and which are provided at their upper ends with 35 forwardly projecting portions 18^a (see Fig. 2) which are designed to be moved over the notched end of lever 16. The plates 17 and 18 are rocked by means of lateral pins 19, one carried upon each of key bars 15" and 15''', and each of which pins operates in a slot in one of plates 17 and 18. By virtue of this arrangement, when these two key bars are operated, the plate 17 of the plate 18 will be rocked forwardly over the end of 40 lever 16 to arrest said lever in its intended position. No stops are operated by the keys 15' or 15'''' to arrest the lever 16 in its predetermined position, for the reason that when bar 15' is operated, it is unnecessary 45 to rock lever 16, and when bar 4 is operated, it will move the lever 16 to the full limit of its movement beyond which it and its associating parts cannot be moved. Lever 16 is connected by a link 20 to the bell crank 21, 50 the upwardly extending arm of which is pivotally connected by a link 22 to the end of lever 8 which carries the movable escapement pallet 7. Lever 8, as heretofore described, is movable longitudinally toward the right a distance sufficient to place the

movable escapement pallet 7 in engagement with teeth of rack 78 either two, three, or four spaces to the right. Upon a pin 9 carried by lever 8 is pivoted a ratchet toothed lever 23 which carries a pin 23^a at its opposite or left hand end. A spring 10 engages the pin 23^a and a stationary portion of the machine, tending to swing ratchet toothed member 23 downwardly. The upper end of bar 6, as shown in Fig. 4, is provided with ratchet teeth 6^a which coöperate with the ratchet teeth on the lower edge of lever 23, and this engagement between bar 6 and lever 23 mounted upon lever 8 causes lever 8 to be swung upwardly and pallet 7 70 disengaged from rack 78 when bar 6 is raised by operation of a key. By virtue of this ratchet engagement, while bar 6 is held elevated it will hold lever 8 elevated with pallet 7 out of engagement with teeth 4, but 75 will permit lever 8 being moved longitudinally so that pallet 7 may be positioned in advance of pallet 5, lever 23 escaping across the upper end of bar 6, and the coöperating teeth on said lever and bar operating to prevent lever 8 being retracted. The means 80 for moving lever 8 longitudinally to position pallet 7 differentially comprises the lever 16, bell crank 21 and link 22, said parts being operated to their fullest extent 85 by operation of key lever 15'''' which engages lever 16 nearest its pivot, to its minimum extent by lever 15" which engages at its end farthest from its pivot, and to intermediate extents by key lever 15''', the extent 90 of its movement by these last two levers being regulated by the plates 17 and 18.

95 The operation of the parts above described is as follows: Upon the initial operation of any one of the multiple space key levers 15", 15''' or 15''''', the bar 56", 56''' or 56''''' corresponding with said key lever is operated to effect upon the elements carried by carriage 57 its intended operation. Simultaneously bar 6 is raised to place the 100 fixed pallet 5 in engagement with rack 78 whereby to hold the carriage against lateral movement. At the end of its upward movement, bar 6 raises pallet 7 out of engagement with the rack 78. When this point in the operation is reached, lever 16 is rocked so as to operate bell crank 21 and through the link connection 22 to draw the lever 8 toward the right a distance of two, three or four teeth depending upon the extent 105 to which lever 16 is rocked by the key lever operating. When the depressed key lever is released and is returning to normal position, vibrating pawl 7 will first be lowered into engagement with the tooth to 110 which it has been positioned, by the lowering of bar 6. Stationary pawl 5 will then be disengaged from the rack 78, and carriage 57 will be moved to the left under the influence of its spring until the end of the 115

slot in lever 8 comes up against its pin 8^a, and the carriage thereby held against further movement.

As above explained, the operation of key lever 15", which is operated by multiple space key 02, will move pawl 7 two teeth to the right so as to permit a leftward letter-spacing movement of carriage 57 a distance of two steps; the operation of key lever 15'", which is operated by multiple space key 03, will in the same fashion produce a letter-spacing movement of three steps; and the operation of key lever 15'", which is operable by multiple space key 04, will produce a letter-spacing movement of the carriage to the extent of four steps.

As vibrating pawl 7 is positioned to the left of stationary pawl 5 a fraction less than a tooth space of rack 78, the raising of bar 6 and without the operation of lever 16 will operate simply to raise pawl 5 into engagement with rack 78 and pawl 7 out of engagement therewith, whereby a slight movement of the carriage is permitted, such movement being sufficient, however, to bring a tooth under pawl 7. The lowering of bar 6 will then disengage pawl 5 from rack 78 and permit the carriage to escape leftwardly until pawl 7 drops in front of the next tooth. In this fashion, the carriage is letter-spaced in single steps, and this single step spacing will be effected by the operation of any one of key levers 2 or key lever 15'.

From the foregoing, it will be obvious that my improved escapement mechanism is adapted to letter-space a movable carriage a predetermined unitary distance, or variable distances consisting of multiples of said unitary distance, and that it is adapted to be operated in conjunction with any mechanism which is adapted to effect upon the carriage or an element carried thereby, variable predetermined operations which are correlated to the different degrees of letter-space movement of the carriage.

I am aware that various modifications and adaptations of my invention may be made by the application of proper skill, and therefore, I do not intend that the scope of my invention shall be limited to the particular form herein shown and described, but that it be construed to comprehend all embodiments employing elements which operate in similar fashions.

What I claim as my invention is:

1. The combination of a traveling carriage and its escapement mechanism, comprising an escapement rack carried by said carriage, a movable pawl capable of being displaced in a direction parallel to the travel of the carriage, key controlled means for determining the distance of displacement of said pawl, a vertically movable bar, a holding dog on said vertically movable

bar, and an extension on said vertically movable bar operatively related to said movable pawl to raise said pawl when said vertically movable bar is raised.

2. The combination of a traveling carriage and an escapement controlling the advance movement thereof, said escapement including a rack carried by said carriage, a pawl mounted for movement parallel with the travel of said carriage, said pawl being normally in engagement with the teeth of said rack to prevent the movement of said carriage, a vertically movable bar, a holding dog on said vertically movable bar, means operatively connecting said vertically movable bar and pawl to disengage said pawl from said rack after said dog is raised into engagement with the teeth of said rack, and means for moving said pawl a predetermined number of rack teeth in the direction opposite to the travel of said carriage, said last mentioned means becoming operative after said pawl has been disengaged from said rack and while said holding dog is in engagement with said rack. 90

3. The combination of a traveling carriage and an escapement controlling said carriage, said escapement including a rack, a pawl mounted for movement parallel with the travel of said rack, said pawl being normally in engagement with the rack teeth, a holding dog, key operated means for bringing said holding dog in engagement with the teeth of said rack and thereafter disengaging said pawl from said rack, and devices for moving said pawl a predetermined number of spaces in the direction of travel opposite the step by step feed of said carriage, and a holding member for preventing retraction of said pawl prior to reengagement of said pawl with the rack teeth. 105

4. The combination of a traveling carriage and an escapement mechanism, comprising a rack, a pawl normally in engagement with said rack, the pawl including an arm provided with a slotted opening, a pivot in said slotted opening to enable said pawl to have both oscillatory and longitudinal movement, a holding dog normally disengaged from said rack, a vertically movable bar on which said holding dog is mounted, an extension on said vertically movable bar, a ratchet bar pivoted on said pawl, ratchet teeth on the end of said extension and in engagement with said ratchet bar, key controlled devices for moving said holding dog into engagement with said rack, and thereafter disengaging said pawl from said rack, and means for moving said pawl a predetermined number of rack teeth 120 in a direction opposite to the step by step travel of said rack.

5. In a device of the character described, a traveling carriage, a rack carried by said traveling carriage, a pawl normally in en- 13

gagement with said rack, a holding dog normally disengaged from said rack, a plurality of key levers arranged in separate groups, a universal bar over all of said groups and operatively connected to bring said holding dog into engagement with said rack and to disengage said pawl from said rack to permit said carriage to have a step by step movement, mechanism operated by certain key levers of one of said groups to move said pawl when disengaged from said rack in a direction opposite to the normal travel of said rack, whereby said rack

may have a step by step movement greater than one tooth of said rack, and devices for retaining said pawl in its moved position until said pawl is reengaged with the teeth of said rack.

In testimony whereof I hereunto affix my signature in the presence of two witnesses, this 8th day of March, 1913.

OTTO THIEME.
